UNITED STATES PATENT OFFICE.

JOHN C. WACHA, OF PROVIDENCE, RHODE ISLAND, ASSIGNOR TO GEORGE H. CAHOONE COMPANY, A CORPORATION OF RHODE ISLAND.

FASTENER FOR CHAINS.

Application filed January 29, 1926. Serial No. 84,746.

To all whom it may concern:

Be it known that I, JOHN C. WACHA, a citizen of the United States, residing at Providence, in the county of Providence and 5 State of Rhode Island, have invented certain new and useful Improvements in Fasteners for Chains, of which the following is a specification.

My invention relates to an ornamental 10 fastening device adapted for use upon ornamental link or bead chains, necklaces, and germane articles of personal adornment.

The essential objects of my invention are to provide in a single ornamental structure 15 a unit adapted to connect either the ends or the intermediate portions of links or bead chains, strings, circlets, necklaces, and the like; to insure security of engagement; adaptability for ornamentation; facility of 20 application and adjustment, and inexpensiveness of construction.

To the above ends essentially my invention consists in such parts and in such combinations of parts as fall within the scope 25 of the appended claims.

In the accompanying drawings which form a part of this specification,

Figures 1 and 2 are a front and plan view 30 respectively of a fastener embodying my invention, the latter being engaged with an intermediate portion of a bead circlet,

Figure 3, a perspective view of an open fastener,

Figures 4 and 5, sections on lines 4—4 of 35 Figure 2 and 5—5 of Figure 4 respectively,

Figure 6, a perspective view of my open fastener partially engaging the ends of one or more strings or ornaments, and

Figure 7, a section of a modified form of 40 my fastener taken on a line corresponding with line 4—4 of Figure 2.

Like reference characters indicate like parts throughout the views.

My fastener consists of a casing 9 having 45 rounded ends, and comprising two oblong hollow substantially semi-ellipsoidal or semi-spheroidal shells formed from thin metal with their adjacent edges in contact with each other. Herein, for convenience of 50 description solely, one of the sections, 10, is referred to as the cover or upper section; while the companion section 11 is styled the lower or body section. Midway their rear edges the sections 10 and 11 have respectively hinge sleeves 12 and 13 embracing a

pintle 14 to form a hinge 15. Opposite the hinge the cover section is provided with a sleeve 17 in which is pivoted a bail 18 adapted to engage a projection 19 upon the body section 11. The whole constituting a 60 catch for maintaining the sections in closed position.

The casing 9 is of a form and construction which lends itself with particular facility 65 to ornamentation by means of graving, stone setting, or interstitial piercing.

Each end of the casing is centrally provided with a hole 21 formed by cavities 22 cut in from the adjacent edges of the shells at the ends of the latter. At each side of the hinge 15 in the back of the casing is a hole 24 formed by cavities 25 formed in the edges of the shells adjacent the hinge. In the front of the casing 9, diametrically opposite the holes 24 are holes 27 formed in 70 each instance by cavities 28 in the forward edges of the shells.

At each side of the center of the body section, in longitudinal alignment with each other are circular openings 30 constituting 75 seats for adjacent ornaments or links of a chain or string of ornaments. Another form of seat for the ornaments, inferior in effectiveness to that described, is indicated in Figure 7 by the reference numeral 31, and consists of a curved depression without 80 any opening, one located each side of the center of the body section.

Of the many uses to which the fastener may be put one is illustrated in Figures 2, 4 and 5 wherein my device is shown embracing an intermediate portion of a bead circlet comprising a strand 35 carrying beads 36. In this application parallel portions of the strand pass through the holes 27 and 24 85 transversely of the casing 9, the latter enclosing one bead 36 of each strand portion. The enclosed beads being held in the seats 30 through which they project by the cover section 10, locked to the body section 11 by 90 the catch.

While the device is applied as described upon either parallel strands or strand portions it may also be employed upon either 105 an intermediate portion of a single strand for the purpose of ornamentation, solely, or upon the ends of the same as a connecting element. In the latter two instances the fastener is applied longitudinally to the strand rather than transversely. In Figure 6, for 110

instance, the ends of a strand or strands 38 are shown carrying beads 39 with alternate knots or spacing beads 40. The chain or strand in such case passes through the openings 21 of the casing.

In order to apply the casing to two parallel chains or chain portions the cover is lifted to the position shown in Figure 3, and the parallel portions are then moved 10 from opposite lateral positions inwardly towards the hinge until the filaments register in the cavities 25 and 28 of the lower section, and a bead or link 36 on each portion rests in a seat 30. Thereupon the cover section is closed and fastened. The casing may 15 be adjusted to any desired position by repeating the described operation.

To apply the casing to a single chain or to the ends of a chain, the casing is disposed 20 as shown in Figure 6, and the chain laid therein longitudinally thereof, and the cover section closed.

I claim:

1. In a fastener of the character set forth, 25 an elongated casing formed in two hollow sections, a hinge connecting the back portions of the sections, a catch connecting the front portions of the sections, said casing being provided in its ends with holes formed 30 by cavities in the edges of the sections, one of the sections being provided with a plurality of longitudinally disposed seats.

2. In a fastener of the character set forth,

an elongated casing formed in two hollow sections, a hinge connecting the back portions of the sections, a catch connecting the front portions of the sections, said casing being provided adjacent each side of the hinge with holes formed by cavities in the edges of the sections, and provided with 40 holes severally opposite the last mentioned holes and formed by cavities in the front edges of the sections, one of said sections being provided with seats spaced from each other between and in transverse alignment 45 with the front and rear holes.

3. In a fastener of the character set forth, 50 a casing comprising two substantially semi-ellipsoidal sections having their adjacent edges in contact with each other, a hinge connecting the back portions of the sections, a catch connecting the front portions of the sections, said casing being provided with holes in its ends formed by cavities in the edges of the sections, and with holes spaced 55 from each other between the first holes formed by cavities in the edges of the sections, and holes diametrically opposite the second mentioned holes and formed by cavities in the edges of the sections, one of said sections being provided on each side of its intermediate portion with seats.

In testimony whereof I have affixed my signature.

JOHN C. WACHA.
